UNITED STATES PATENT OFFICE.

BALTHASAR KREISCHER, OF NEW YORK, N. Y.

DESIGN FOR HOLLOW TILES.

Specification forming part of Design No. 5,140, dated July 25, 1871.

To all whom it may concern:

Be it known that I, BALTHASAR KREISCHER, of the city, county, and State of New York, have invented a new and original Design for Hollow Tiles; and I do hereby declare the following to be a full, clear, and exact description thereof, which will enable those skilled in the art to make and use the same, reference being had to the accompanying drawing forming part of this specification, in which drawing—

Figure 1 represents a transverse section of my tile. Fig. 2 is a side view of the same.

Similar letters indicate corresponding parts.

This design relates to a hollow tile, the bottom of which is flat and provided with projecting flanges, while its sides are vertical and provided with angular recesses, in such a manner that a tile is obtained, which, when inserted between two wooden beams, will lie close against said beams and form a protection against fire, while the angular recesses, when made to catch over strips secured to the beams, form the supports for the tile, and the bottom flanges extend beyond the edges of the beams and serve to support filling-strips which protect the lower sides of the beams.

In the drawing, A designates a hollow tile, which is made with a flat bottom, B, and with

flanges C formed as shown in Fig. 1. The sides D of my tile are vertical, and they are provided with recesses a, as shown. This tile is made to fit nicely between two wooden beams in a building, being supported by strips of wood nailed against the sides of said beams and catching in the recesses a. By the vertical sides of the tile fitting closely to the sides of the beams said beams are protected against fire, and a fire originating in the top of a building cannot spread downward, since there is no draught from below, and the beams will only be charred as far as they project above the tiles inserted between them. The bottom flanges C are dovetailed to receive filling-strips, which are intended to protect the under surfaces of the beams.

From this description it will be readily understood that by giving to my tile the form or shape above described certain new and important results are attained which cannot be attained by hollow tiles made in different forms.

What I claim as new, and desire to secure by Letters Patent, is—

The design for a hollow tile, as herein shown and described.
